UNITED STATES PATENT OFFICE.

HENRY FERESTER, OF BROOKLYN, NEW YORK.

CONTROL DEVICE.

1,394,158.

Specification of Letters Patent.

Patented Oct. 18, 1921.

Application filed September 18, 1919. Serial No. 324,649.

To all whom it may concern:

Be it known that I, HENRY FERESTER, citizen of the King of Roumania, and resident of Brooklyn, in the county of Kings and 5 State of New York, have invented certain new and useful Improvements in Control Devices, of which the following is a specification.

This invention relates to controlling or 10 tripping devices for electrical and mechanical machinery, and has for its object to provide such a device which can be readily operated by one positioned at a distance from the device, whereby my invention is a means 15 of saving both time and labor.

Another object of my invention is to provide a control device, operable at a distance, for controlling the reciprocating action of a lever, rod, punch, drill, or the like such as 20 are used on milling machines, drill presses, and the like.

The above and other objects will become apparent in the description below, in which characters of reference refer to like-named 25 parts on the drawings.

Referring briefly to the drawings, Figure 1 is a plan view of my device.

Fig. 2 is a side elevational view of the same.

Fig. 3 is a plan view of a modification of 30 the device shown in the above figures.

Fig. 4 is a perspective view of the same.

Referring now in detail to the drawings, the numeral 1 represents the frame or bed 35 plate of my device, the same being provided with vertical end pedestals or supports 2 and 3. Said supports contain bores or bearings for the shaft 6, said bores being surrounded, outside the support, with tapering 40 collars 4. The cross-section of said shaft 6 is of different forms at different parts of its length. The same is circular at the left of the figure, square at 7 about the center, square again at the right of said section 7, 45 at 9, but displaced 90 degrees from the square of said section 7, and finally circular again so that the shaft may lie in the bearing in the support 3.

A flange 8 is rigid to said shaft at the dividing line between the sections 7 and 9. A similar flange 8 is rigid to the inside of the support 3, surrounding the bore in said support. A strong coiled spring 10 surrounds said shaft between said flanges 8. The right

hand end of said shaft is provided with a 55 collar and eye 12.

A rectangular pocket or slot 17 is cut at the central portion of the upper part of section 7 of said shaft. A finger 18 projects into said pocket so the transverse motion of 60 said finger will impart longitudinal motion to said shaft. Said finger 18 is rigid to and part of a prong or lever 13 which is pivoted on a pin 14, the latter being surrounded by a sleeve 15 and supported in the frame 5. Said 65 frame 5 is secured to the base of the bed plate 1 by means of bolts or rivets 19. The lever 13 is provided with an eye or hole 20. A second lever 13^a, similar to said lever 13, is integral with the latter and provided with a 70 similar eye. Said levers 13 and 13^a are mutually displaced at an angle of 90 degrees.

The operation of the device is now apparent, and is as follows: Strings of cord or wire 22 is inserted into each of the holes 20 75 and 21, the other ends of said strings being located near the operator of the machine. As an example, assume that a tripping bar is attached to the eye 12, and that said bar controls the descent of the drill of a drill 80 press. The only operation needed to control the above is reciprocation of said bar. Pulling either of the strings will cause the shaft 6 to move against its spring, and releasing the string will allow it to return. It is apparent that, by use of the double lever 13—13^a, my device may be operated from 85 nearly any part of the room, for, when the lever 13 is inoperative because the string therein is in line with said lever, then the 90 lever 13^a will be operative, and vice versa.

My device may also be operated by a foot-controlled mechanism or linkage, so that a single depression by the foot will actuate the device as above described. This is of especial value in the case of drill presses or the like, where I make my said linkage pass around the side of the mouth of the press so that the same does not interfere with the operation of the press and the insertion of 100 and removal of working material from the press.

In Figs. 3 and 4 I have shown a form of my device which is useful on machines at present controlled by electromagnets, instead of by hand, as in my above described device. Frequently the electromagnets burn out, or the electrical system fails in some 105

way, so that the machine must remain idle until necessary repairs are made. My last mentioned device eliminates this loss of time in case the electromagnet becomes inoperative.

In this device 22 represents the main beam or member having slots 29 therethrough near the ends, and a hole adjacent the right hand slot 29. Pins, or the shanks of bolts, 28, pass 10 through said slots and hole, those through the slots being rigid to L members 24 and 25, respectively, and that through the hole being rigid to the rocking lever 26. The member 22 is bent upward at the left so as to provide 15 a support, properly carved out at the top, for the reception of the core of the electromagnet which has become inoperative, and which my device will replace. The bracket or L members 24 and 25 are attached to a 20 suitable wall or the like by means of screws through the holes 27. The member 22 is provided with an end eye 32.

Now it is apparent that, when the strings attached to the complementary arms of the 25 member 26, are situated near the operator of the machine, at whatever distance from the machine, the operator can, by pulling either of the strings, cause the member 22 to move longitudinally a sufficient distance to operate 30 the machine as described in the first part of this specification. Since the burnt out electromagnet is always provided with a spring similar to the spring 10, said magnet will upon release of the string return to its normal position.

Having thus described my invention, what I claim as new and desire to secure by Letters Patent is as follows:

1. In a device of the class described, a 40 supporting member, a bar resiliently slidable

longitudinally therein, means for actuating said bar comprising a pair of complementary arms fulcrumed at or near their point of intersection, and a member projecting from said point and engaging said bar.

45

2. In a device of the class described, a supporting member, a resilient member slideable therein, a bracket rigid to said supporting member, means for actuating said resilient member comprising a pair of complementary arms fulcrumed at or near their point of intersection to said bracket, and a member projecting from said point and engaging said member.

50

3. In a device of the class described, a supporting member, a resilient member slideable therein, means for actuating said resilient member comprising a pivoted sector having a plurality of eyes or the like, and a member projecting from said sector and engaging with said resilient member.

60

4. In a device of the class described, a supporting member, a resilient member slideable therein comprising a shaft having a central portion of square cross-section and a 65 pair of spaced-apart flanges, one of said flanges being rigid to said shaft and the other being rigid to or part of said supporting member, a coiled spring surrounding said shaft between said flanges, a pocket in 70 said shaft, a bracket rigid to said supporting member, a pair of complementary arms pivoted to said bracket, and a member projecting from said arms and engaging said pocket, and means attached to the ends of 75 said arms.

75

Signed at New York, in the county of New York and State of New York, this 9th day of Aug., A. D. 1919.

HENRY FERESTER.
